UNITED STATES PATENT OFFICE.

BENJAMIN PETROWSKY, OF NEW YORK, N. Y., ASSIGNOR TO PARAGON AUTO PARTS MFG. CO., INC., OF NEW YORK, N. Y., A CORPORATION OF NEW YORK.

DESIGN FOR A FILM REEL.

Application filed May 18, 1925. Serial No. 13,477. Term of patent 7 years.

To all whom it may concern:

Be it known that I, BENJAMIN PETROWSKY, a citizen of Russia, and a resident of the city of New York, borough of the Bronx, in the county of Bronx and State of New York, have invented a new, original, and ornamental Design for Film Reels, of which the following is a specification, reference being had to the accompanying drawing, forming part thereof.

I claim—

The ornamental design for a film reel as shown.

BENJAMIN PETROWSKY.
